 9 Claims. (Cl. 137—357)

The present invention is concerned primarily with the problem of utilizing the potential energy of a liquid for the direct production of vacuum within a closed vessel.

One object of the invention is to provide an improved hydraulically operated gas pump of the kind in which liquid is introduced batchwise into the top end of a standpipe or standpipes so as to form therein spaced successive liquid bodies or plugs filling out the cross-sectional area of said pipe or pipes and removing between them gas from an enclosure communicating with said standpipe or standpipes.

A particularly important object of the invention is to provide a hydraulic gas pump of the kind referred to which, without reduction of its efficiency, can be designed for high pumping capacity, i.e. with a standpipe or standpipes of substantial cross-sectional area, for instance for use of the potential energy of high natural heads of water.

A further object of the invention is to provide a hydraulic air pump of a simple construction in which the potential energy of waste or sewage water discharged from the upper floors of a building into a sewer or any other outlet conduit can be utilized for producing a vacuum.

Another object of the invention is to utilize a vacuum produced in this or in any other way for sucking domestic sewage onward through substantially horizontally disposed conduit sections, thus eliminating the usual requirement for a steep slope towards the outlet end of such conduit sections, and enabling the conduits concerned to be narrower than has been possible before.

According to this invention, there is provided a hydraulically operated gas pump, particularly a vacuum pump, in which liquid is introduced batchwise into the top end of a standpipe so as to form therein spaced successive liquid plugs completely filling out the cross-sectional area of the pipe and adapted to carry away between them gas withdrawn from an enclosure communicating with the standpipe, wherein, for controlling the amount of liquid supplied to the standpipe in each batch, the standpipe is provided at its top end with a valve adapted to open and close periodically, and a branch pipe communicating with the enclosure to be evacuated is connected to the standpipe downstream of said valve.

Further features and advantages of the invention will become apparent from the following detailed description of preferred embodiments and applications thereof given by way of example with reference to the accompanying drawings, in which:

FIGURES 1, 2 and 3 show diagrammatically one embodiment of hydraulic gas pump according to the invention in different stages of its operating cycle;

FIGURE 4 illustrates diagrammatically a modified hydraulic gas pump;

FIGURE 5 shows a vertical section through a hydraulic gas pump comprising a closed float vessel and an influent inlet connected thereto and containing a float-controlled cut-off valve;

FIGURE 6 shows a vertical section through a building in which a plurality of vacuum-producing apparatus according to FIGURE 5 are installed, such apparatus being adapted to be operated by sewage supplied from the overlying floors;

FIGURE 7 is a diagrammatic vertical section through

2

apparatus for producing vacuum utilizing the potential energy of a natural water basin or stream; and

FIGURE 8 is a side view of a valve assembly useful in the pump arrangement of FIGURE 5.

Referring to FIGURES 1 to 3 of the drawings, numeral 10 designates an open-topped vessel or receptacle communicating through a central bottom opening with a substantially vertical standpipe 11, the bottom end of which is submerged below the surface of a water pool 12. Disposed in the receptacle 10 is a float 13 formed at its bottom end with a conical valve member 14 adapted, when the float is in its lowermost position, to rest on a conical valve seat 15 formed around the bottom opening of the float vessel 10. The float 13 is slidably guided in the float vessel by guide ribs 16 provided on the inner wall surface of the vessel. Numeral 17 designates an inlet through which water or any other liquid is fed continually or batchwise into the float vessel.

Opening into the vertical standpipe 11 immediately below the float vessel 10 is a branch pipe 18 which communicates with a closed vessel or enclosure (not shown) of comparatively large capacity and in which a vacuum is to be maintained. Inserted in the branch pipe 18 adjacent to the standpipe 11 is a non-return valve 19 which opens towards the standpipe so as to permit the flow of air from the enclosure into the standpipe, but prevent the flow of air or water from the standpipe into the enclosure.

The vacuum-producing apparatus described operates as follows.

A certain degree of vacuum is assumed to prevail within the large closed vessel with which the branch pipe 18 communicates. Consequently, a liquid column 20 of the height h is established in the standpipe 11. The float vessel 10 is assumed to be only partially filled with liquid, so that the float 13 will be in its lowermost position in which the bottom opening of the float vessel is closed. In this position the float 13 is acted on by a downwardly directed force established by the sum of the weight of the float and the suction head caused by the vacuum existing in the standpipe and acting on the area of the conical valve member 14 exposed to the interior of the standpipe 11, less an upwardly directed force which is proportional to the mass-weight of the body of water displaced by the float. As the liquid level rises within the float vessel 10 this mass-weight will increase, and finally a point will be reached at which the upwardly directed force exerted on the float by the liquid body concerned will exceed the sum of the downwardly directed forces. At this moment the float will begin to move upwardly. When the float has risen to an extent allowing liquid to enter the standpipe 11, such liquid will compensate for the suction acting on the exposed bottom face of the valve member so that the suction will rapidly diminish or cease, thus causing a sudden decrease of the total downward force exerted on the float. As a consequence the float will rapidly be lifted to the position determined by the quantity of liquid present within the float vessel 10, thus completely uncovering the bottom opening of the float vessel.

Liquid from the float vessel 10 will now rapidly flow into the standpipe 11, whilst forming therein a liquid plug or "piston" 21 completely filling out the cross-sectional area of the standpipe. The inflow is initially accelerated by the vacuum prevailing in the standpipe 11 above the liquid column 20. As, under the action of gravity, the liquid plug 21 drops deeper down the standpipe 11 at an accelerated velocity, the pressure of the volume of air, 22, trapped between the liquid plug 21 and the liquid column 20 will be increased, thus causing the liquid column 20 to begin to fall within the standpipe 11. At the same time the liquid level within the float vessel 10 will sink

causing the float 13 to move downwardly and, finally, to seat its bottom end forming the conical valve member 14 on the valve seating 15, whereby the downflow of liquid into the standpipe will be interrupted. Now, if the capacity of the float vessel 10 has been suitably dimensioned, a sufficient quantity of liquid will have been admitted into the standpipe 11 to cause the length of the liquid plug 21 formed therein to be considerably in excess of the original height h of the liquid column 20. Therefore, the liquid plug 21 will continue to drop down the pipe 11 whilst displacing the entire liquid column 20 and the volume of air, 22, on top of this column and will itself occupy the place previously occupied by the liquid column 20.

When, in the sequence of events just described, liquid from the float vessel 10 entered the standpipe 11 tending to increase the pressure therein, and, because this pressure is directed toward the pipe 18, this will cause the non-return valve 19 to close, so as to prevent liquid from flowing into the branch pipe 18 in which a vacuum exists. Upon closure of the float valve 14, 15, there will have been created behind the gravitating liquid plug 21 a vacuum which releases the non-return valve 19 which will reopen, and during the continued descent of the liquid plug air from the vacuum enclosure will be sucked into the standpipe 11, thus causing a fresh charge of air to collect above the liquid plug within the standpipe. At the same time, the absolute pressure within the vacuum enclosure will, owing to the sucking of air into the standpipe, have been reduced so that the new liquid column, which replaces the previous column, will be somewhat higher than the latter. When a sufficient liquid quantity has again collected in the float vessel 10, the latter will empty a new liquid plug into the standpipe 11, thus repeating the above-described cycle of operations while pumping out air batchwise from the vacuum enclosure. On account of the gradually increasing vacuum within the vacuum enclosure and within the standpipe 11 communicating therewith, the downwardly directed force acting on the float 13 due to the vacuum will be increased on completion of each pumping cycle, so that after the discharge of each batch of liquid into the standpipe 11 a greater upward force acting on the float will be required to cause opening of the float valve. This means that the float valve 14, 15 will open at successively increasing liquid levels within the float vessel 10, whereby successively increasing quantities of liquid will be discharged into the standpipe so as to form gradually increasing liquid plug lengths in this pipe. It is possible, by suitably dimensioning the float vessel and float, to establish a condition in which, during each valve-opening operation there will only be discharged into the standpipe a quantity of liquid sufficient to form a plug of the length necessary having regard to the vacuum actually reached in the enclosure, whereby a high pumping efficiency may be expected.

One pre-requisite for satisfactory operation of the vacuum producer described resides, of course, in that the liquid supplied in metered quantities from the float vessel into the standpipe will actually fill out the cross-sectional area of the standpipe and will drop down through this pipe as a perfectly integral liquid plug which forms a sealing partition between the vacuum enclosure and the body of air entrapped below the descending liquid. In the embodiment shown, an immediate and perfect filling-out of the standpipe cross-sectional area without any admixture of air has been provided for by causing the float valve 14, 15 controlling the liquid discharge into the pipe to be maintained submerged in the liquid within the float vessel 10. By forming the bottom portion of the float substantially as a cone, the liquid is caused to flow radially inward towards the mouth of the pipe from all sides, so that right from the beginning there will form a solid plug in the standpipe, provided the valve opening takes place

at a sufficiently rapid rate once the valve has commenced its opening movement.

A sudden increase of the valve-opening force before the valve cone has begun to move off its seat may be attained by supplementing the design of the float valve arrangement in the manner illustrated in FIGURE 4.

As shown in this figure, a tilting vessel 23 known per se, is mounted on the top of the float 13. This vessel is tiltable about a horizontal pivot axis 24 and comprises two identical pockets 25 and 26 symmetrically disposed relative to the tilting axis. Either of the pockets 25, 26 is always positioned below a spout 27 through which a suitably metered small proportion of the amount of liquid supplied through the inlet pipe 17 is allowed to flow into said pocket. The rate of outflow through the spout 27 is suitably metered in such a way as to cause the pocket to be completely filled immediately before the liquid within the float vessel 10 has reached a level at which the lift exerted on the float is just sufficient to outweigh the sum of the forces tending to move the float in a downward direction. As soon as the pocket, e.g. pocket 26, disposed beneath the spout has been filled up to a predetermined level, the vessel 23 will tilt, thus discharging the liquid gathered in this pocket into the float vessel 10 whilst simultaneously positioning the other pocket, e.g. pocket 25, beneath the spout. The emptying of the pocket 26 will cause a sudden decrease of the downward force acting on the float 13 by the weight of the liquid quantity thus discharged, and at the same time a sudden increase in the liquid level within the float vessel will occur. As a result, the float will move upwardly at a rapid rate thus completely opening the passageway between the float vessel 10 and the standpipe 11.

It is a desideratum also that, once the valve has closed, it shall remain closed until the next-succeeding metered discharge is to be initiated. As is well known, a float-controlled discharge valve moves towards its seating at an accelerated rate immediately before it engages the same. The cause of this effect resides in a pressure reduction in the liquid due to its velocity, the so-called Bernoulli's pressure reduction. As soon as the valve closes, this pressure reduction will cease, and at the same time the liquid mass displaced by the float is increased, so that the valve is caused to reopen momentarily. In order to prevent such oscillation of the valve in conjunction with its closing, the apparatus may be supplemented with a damping or inertia mechanism of any suitable construction, which may be known per se.

Where the internal diameter of the standpipe is so large that the capillary forces cannot play any effective part in the maintaining of the plug in a coherent state, a certain falling velocity of the liquid plug will be required to keep the same together as a unit during its movement through the standpipe. The minimum falling velocity will be the higher, the larger is the diameter of the standpipe. As already stated, it will be necessary, in order to obtain a sufficient falling velocity of the plug, to discharge each time a liquid quantity so proportioned as to cause the length of the plug formed to exceed the height of the liquid column present in the lower portion of the standpipe.

Particularly in large installations it may be suitable, for controlling the liquid dosage or apportioning valve, to employ, instead of a float, a special mechanism adapted to open the valve when a sufficient quantity of liquid has collected in the vessel for forming a liquid plug of the desired length, and to cause closure of the valve after the elapse of a time the length of which is properly related to the vacuum actually existing in the vacuum enclosure. Such a mechanism, if suitably constructed, may be operated utilizing the potential energy of the liquid proper.

FIGURE 5 shows a vacuum producer of a slightly modified design and intended primarily to be employed in cases where the liquid, the potential energy of which is to be utilized for vacuum production, cannot simply

flow freely to the float vessel inlet. The vacuum producer illustrated in said figure is thus intended primarily for utilizing the potential energy of bath water, slops and other dirty water let out into a sewerage system from the upper floors of a building.

According to FIGURE 5, the float vessel 10 is provided with a tight-fitting cover 29 so that the interior of the vessel is hermetically enclosed and thus separated from the ambient air. The cylindrical wall of the vessel is formed at a short distance beneath the cover 29 with a circumferential row of spaced openings each having connected to it in a gas tight manner a corresponding one of a plurality of liquid inlet pipes 30, which are preferably made of flexible plastic tubing. Each pipe 30 is provided at its opposite end with a normally closed valve, for instance a float-operated valve 31. Disposed underneath the cover 29 is a cylindrical baffle or skirt 32 adapted to prevent liquid entering through the respective pipes 30 from impinging on the float 13. The baffle also serves as a guide for the float. In order to promote the conveyance of the liquid from the respective wash basins or the like to the float housing 10 disposed at the same floor a certain vacuum is maintained within this housing. The absolute pressure within the float housing 10, however, must be substantially in excess of the absolute pressure within the vacuum enclosure and its associated branch pipe 18 in order to enable the float valve to function in the manner described in conjunction with FIGURES 1, 2 and 3. Such a reduced vacuum is maintained within the float vessel 10 by the provision of a by-pass 33 through which the air space of said vessel is connected with the branch pipe 18 and which contains a pressure control valve 34 adapted to close automatically as the difference between the pressures on either side of the valve drops below a predetermined value.

Referring to FIGURE 8 which illustrates the pressure control valve 34 in the pipe 33, there is included a nipple 78 in which a circumferential valve seating 79 is provided. A non-return valve member in the form of a flap 80 is fixedly attached to a pin 81 rotatable in a projection 82 of the nipple 78. That portion of the pin 81 which is rotatably mounted in the projection 82 is of circular cross-section and adapted to provide a seal against the projection.

The pin 81 projects on the outside of the projection 82 and has mounted thereon a lever arm 83 that is secured by a pin 84. A weight 85 is attached to the arm 83 and is displaceable therealong to provide an adjustable moment about the pin 81. The weight may be fixed in position by a set screw 86.

It will be apparent that the valve member 80 retains the passage through the nipple 78 closed as long as the pressure difference acting on the valve member produces a clockwise moment about the pin 81 that is less than the counterclockwise moment about the pin produced by the weight 85. Thus, when the pressure within the float vessel 10 exceeds that in the branch pipe 18 by an amount sufficient to produce a clockwise moment about the pin 81 greater than the counterclockwise moment produced by the weight 85, the valve member 80 is swung to an open position, allowing the pressure within the housing 10 to be reduced until the valve member swings closed.

The above-mentioned float valve 31 disposed at said opposite end of each liquid inlet pipe 30 comprises, as seen in FIGURE 5, a float housing 35 and, disposed therein, a float 36 mounted for vertical movements within the float housing by being guided between ribs 37 provided therein. In the lowermost position of the float, as shown in the drawing, its conically shaped bottom end sealingly engages a correspondingly shaped seating formed at the junction between the housing and a pipe socket 39 to which the above-mentioned plastic tube 30 leading to the float vessel 10 is connected, whilst in its uppermost position the float abuts a distributing plate 40 mounted in spaced relation with the underside of the float-housing

cover. Through a pipe socket 41 provided centrally in the latter, the float housing 35 may be connected to the outlet conduit from a wash basin 42 or the like, so that liquid will flow into the float housing and will lift the float when the bottom outlet of the wash basin is opened. 5 Each time this occurs, liquid will be sucked through the conduit 30 into the float vessel 10 of the vacuum producer. When the wash basin 42 has been emptied, and the liquid level within the float housing 35 of the cut-off valve 31 has fallen off sufficiently to cause this valve to close, the inflow of liquid into the float vessel 10 is interrupted. As the liquid enters and begins to fill the float vessel 10, a corresponding amount of air is sucked out through the valve 34 whereby the vacuum within the 10 float vessel 10 is maintained substantially constant. In 15 a similar way, liquid is sucked batchwise into the float valve housing 10 through the inlet pipe 30 from any other wash basin or the like connected thereto. As the free liquid surface within the float housing 10 has risen to a 20 level determined by the vacuum existing in the branch pipe 18, the float 13 is rapidly unseated and suddenly discharges the collected quantity of water into the standpipe 11, and then re-closes before the float housing has 25 become completely emptied of its liquid content, as described in conjunction with the embodiment shown in FIGURES 1 to 3.

The above-described vacuum producer comprising a sealed-off float vessel 10 and a standpipe 11 the lower end of which is immersed into liquid 12 is obviously dependent, for its proper operation, on the maintenance of a certain minimum vacuum value within the vacuum enclosure or tank which is common to a plurality of apparatus and with which the branch pipe 18 communicates. To the end of removing such dependence, there is mounted, according to FIGURE 5, within the branch pipe 18, beyond the point where the by-pass conduit 33 opens into this branch pipe, a cut-off valve generally designated by 45 and adapted to close automatically if the vacuum within the float vessel 10 should drop below a predetermined 30 value. The valve 45 is shown in the drawing as a butterfly valve pivoting about the axis 46 and urged towards its closed position by the action of a weight-loaded lever 47. The lever 47, however, is normally held in a raised position corresponding to the open position of the valve 40 by a piston 48 adapted to slide within a cylinder 49 and connected to the lever by a link 50. The cylinder space above the piston communicates with the air space of the float housing 10 through a pipe 51 whereby, as long as a 45 vacuum of sufficient magnitude exists within the float housing, the piston is retained in its upper limit position, as shown, whereas, if the air pressure within the float housing should exceed said predetermined value, the piston will descend through its cylinder and thus cause the valve to close.

50 A pre-requisite for the possibility of utilizing the potential energy or head of slops and other waste water for vacuum production while using comparatively narrow conduits is, of course, that such water is relatively free from solid refuse or excrements discharged from water closets. 55 FIGURE 6 illustrates a complete building sewage handling system in which the vacuum produced by utilizing the waste water head is used for the conveyance of the refuse from the water closets through a separate conduit system to a collecting tank under vacuum, whereas the ordinary waste water is conducted to the sewerage system through vacuum production apparatus constructed in accordance with the present invention.

60 Referring to said FIGURE 6, numeral 52 designates a vacuum enclosure or tank, numeral 53 denotes two vacuum producers of the kind shown in FIGURE 5 and mounted at the second and third floors, respectively, and numeral 54 denotes a bath tub, 55 a wash stand and 56 a dish-washing sink at the respective floors. Each vacuum producer 53 is connected to the building sewer 57 65 by an individual standpipe 11, whilst a pipe 58 common

to the two vacuum producers shown interconnects the vacuum tank 52 with the branch pipe 18 of each of the vacuum producers. The outlet conduits from the bath tubs, wash stands and sinks installed at the corresponding floors are connected, through individual float-controlled valves of the kind illustrated in FIGURE 5, to conduits 30 which open into the float vessel 10 of the respective vacuum producers, as shown in FIGURE 5. Those bath tubs, wash stands and sinks which are installed at the bottom floor may also be similarly connected, by a conduit 30, to a closed collecting vessel 59 within which a vacuum which ensures liquid flow through a conduit rising in the direction of flow therethrough is maintained in the same way as within the float housings of the vacuum producers 53. The vessel 59 is provided with a float-controlled bottom valve through which the collected waste water is intermittently discharged into the sewer 57 through an outlet conduit 60.

The vacuum produced within the vacuum tank 52 is utilized, in addition to its utilization for sucking the bath water and other waste water through the relatively narrow horizontal conduits 30 into the float vessels of the vacuum producers 53, and into the collecting vessel 59, respectively, also for the withdrawal of excrements, urine and flushing water from the water closets 61 through the narrow discharge outlet pipe 62 to a closed collecting or disposal tank 63 which is connected to the vacuum tank 52 through a pipe 64 and in which, therefore, a vacuum permanently exists. Such a water closet system is disclosed in my copending application Serial No. 184,632 filed March 22, 1962.

FIGURE 7 illustrates a vacuum producer of the type shown in FIGURES 1 to 3, i.e. having an open-topped float vessel, which is arranged for utilizing the potential energy or head of the water in a high-level natural water reservoir for the production of a vacuum within an enclosure, or closed tank.

In this figure, as before, numeral 10 designates the float vessel or housing, numeral 11 the standpipe, numeral 12 a lower-level body of water into which said pipe is immersed, numeral 18 the branch pipe and numeral 19 the non-return valve inserted therein adjacent to the standpipe. The vacuum tank to which the branch pipe 18 connects is designated by 65. Numeral 66 diagrammatically indicates a weir extending, for instance, across a river. Formed through the weir 66, which forms one lateral wall of the float vessel 10, is an opening 67 which is controllable by a flap 69 pivotable about an axis 68. Through the inlet opening 67 water continually flows from the reservoir upstream of the weir into the float vessel at a rate of flow corresponding to the effective opening area provided by the flap 69. The liquid collected within the float vessel is discharged periodically into the standpipe 11 under the control of the float 13, as described hereinbefore in conjunction with FIGURES 1 to 3, thus creating each time in the standpipe a liquid plug or "piston" causing a quantity of air to be sucked out from the vacuum tank 65 whereby the air pressure therein is gradually reduced. After a desired degree of vacuum has been reached within the vacuum tank, the operation of the vacuum producer should desirably be stopped, or its rate of operation should at least be reduced. In order to enable an automatic adaptation of said rate of operation to the momentary requirements, a regulating mechanism is provided comprising a vertical cylinder 70 which is connected at its top end to the vacuum tank 65 through a pipe 71 and in which reciprocates a piston 72 having a depending piston rod 73 carrying a cam member 74 with which a cam-follower roller 75 mounted on the flap 69 is adapted to co-operate. When the piston 72 is in its lowermost position, which is the case when atmospheric pressure exists within the vacuum tank 65, the flap is wide open. As the vacuum increases within the tank 65, the piston 72 is sucked further into the cylinder 70 pulling at the same time behind it a water column 76

serving as a counter-weight. During this movement the cam member 74 urges the roller 75 to move continuously to the right according to the figure, whereby the flap is pivoted continuously towards its closed position which it reaches as the maximum vacuum desired has been reached. As the vacuum diminishes again this causes downward movement of the piston 72 together with the cam member 74, so that the flap valve 69 is re-opened and the vacuum producer resumes its operation at a rate corresponding to the consumption of vacuum.

Instead of a liquid column sucked into the cylinder being used as a counterweight a chain or the like could be used, such chain being fastened at one end to the piston 72 and supported at its lower end on a stationary base whereby the length of the chain part hanging down from the piston will increase as the piston moves upward into the cylinder.

The standpipe 11, which might be inclined at a relatively small angle to the horizontal and thus may have considerable length, may be formed with one or more plug-restoration pockets or loops 77. Similar pockets or loops could of course be associated also with the standpipes of other constructional forms of the vacuum pump according to the invention.

What I claim is:

1. A building sewerage system for carrying away waste water, comprising waste water receiving apparatus having an outlet, a hermetically sealed collecting vessel, means for maintaining a sub-atmospheric pressure in said collecting vessel, conduit means connecting the outlet of said waste water receiving apparatus to said collecting vessel, a shut-off valve inserted in said conduit means, means for moving said shut-off valve from a closed to an open position in response to the discharge of liquid from said waste water receiving apparatus and to reclose said shut-off valve when said discharge ceases, an outlet from said collecting vessel, and means to discharge the contents of said collecting vessel, wherein said conduit means comprises flexible tubes of plastic material.

2. A building sewerage system for carrying away waste water comprising waste water discharging apparatus from which waste water is to be carried, a collecting vessel having an inlet and an outlet, conduit means coupling said inlet of said collecting vessel to an outlet of said waste water discharging apparatus and through which said waste water flows from said waste water discharging apparatus to said collecting vessel, a sealed enclosure coupled to the outlet of said collecting vessel, a cut-off valve positioned in the outlet of said collecting vessel between the collecting vessel and the point at which the enclosure is coupled to said outlet, means for opening said cut-off valve when the waste water in said collecting vessel rises to a first predetermined level, and means for closing said cut-off valve when the waste water in said collecting vessel falls to a second level lower than said first level, whereby a vacuum is produced in the enclosure upon the discharge of waste water through the outlet of said collecting vessel and the waste water in the collecting vessel is periodically discharged.

3. In combination with a building sewerage system as recited in claim 2 wherein said collecting vessel is a sealed enclosure, a line coupling the vacuum enclosure to said collecting vessel through a cut-off valve whereby a vacuum is produced in said collecting vessel and is held at a predetermined value.

4. A building sewerage system for carrying away waste water, comprising waste water discharging apparatus from which waste water is to be carried, a hermetically sealed collecting vessel having an inlet and an outlet, conduit means coupling said inlet of said collecting vessel to an outlet of said waste water discharging apparatus, a sealed enclosure coupled to the outlet of said collecting vessel, a first cut-off valve positioned in said conduit means, a second cut-off valve positioned in the outlet of said collecting vessel between the collecting vessel and the point

at which the enclosure is coupled to said outlet, means responsive to the discharge of liquid through the outlet of said waste water discharging apparatus for opening said first cut-off valve, means for opening said second cut-off valve when the liquid in said collecting vessel rises to a first predetermined level, and means for closing said second cut-off valve when the liquid in said collecting vessel falls to a second level lower than said first level, whereby a vacuum is produced in the enclosure upon the discharge of liquid through the outlet of said collecting vessel.

5. In combination with a building sewerage system as recited in claim 4, pipe means coupling a space above the liquid in said collecting vessel to said enclosure, and valve means positioned within said pipe means for maintaining the pressure in said space in said collecting vessel at a pressure greater than the pressure in said enclosure and less than atmospheric pressure.

6. A building sewerage system for carrying away waste water, comprising waste water receiving apparatus having an outlet, a hermetically sealed collecting vessel, means for maintaining a sub-atmospheric pressure in said collecting vessel and for discharging the contents of said collecting vessel, pipe means connecting the outlet of said waste water receiving apparatus to said collecting vessel, a shut-off valve inserted in said pipe means, means for moving said shut-off valve from a closed to an open position in response to the discharge of liquid from said waste water receiving apparatus and to reclose said shut-off valve when said discharge ceases, and an outlet from said collecting vessel, wherein said means for maintaining a sub-atmospheric pressure in said collecting vessel and for discharging the contents of said collecting vessel comprises a downwardly extending discharging standpipe coupled at its upper end to the outlet of said collecting vessel, means for discharging water batchwise from said collecting vessel to form integral plugs of water completely filling out the cross-sectional area of said standpipe, and pipe means connecting said collecting ves-

sel to the upper end of said standpipe, whereby, as said plugs of water gravitate through said standpipe, the air is sucked out of said collecting vessel.

7. In combination with the building sewerage system as recited in claim 6, a vacuum enclosure connected to the upper end of said standpipe, whereby, as said plugs of water gravitate through said standpipe, the air is sucked out of said vacuum enclosure.

8. A building sewerage system for carrying away waste water, comprising waste water receiving apparatus having an outlet, a hermetically sealed collecting vessel, means for maintaining a sub-atmospheric pressure in said collecting vessel, pipe means connecting the outlet of said waste water receiving apparatus to said collecting vessel, a shut-off valve inserted in said pipe means, said shut-off valve comprising a float disposed in a hermetically-sealed float housing through which the discharged waste water flows, means for moving said shut-off valve from a closed to an open position in response to the discharge of liquid from said waste water receiving apparatus and to reclose said shut-off valve when said discharge ceases, an outlet from said collecting vessel, and means to discharge the contents of said collecting vessel.

9. A building sewerage system according to claim 8, wherein said float housing is in the form of an upright elongated cylinder having a bottom opening controlled by said float.
